SIMEON S. JACKSON, OF BOSTON, MASSACHUSETTS, ASSIGNOR TO THE STAFFORD COMPANY, OF READVILLE, MASSACHUSETTS, A CORPORATION OF NEW JERSEY.

WEFT FEELER MECHANISM FOR LOOMS.

1,300,971.

Specification of Letters Patent. Patented Apr. 15, 1919.

Application filed May 12, 1916, Serial No. 97,189. Renewed August 15, 1918. Serial No. 250,077.

To all whom it may concern:

Be it known that I, SIMEON S. JACKSON, a subject of Great Britain, residing at Boston, in the county of Suffolk, State of Massachusetts, have invented a certain new and useful Improvement in Weft Feeler Mechanism for Looms, of which the following is a specification, reference being had therein to the accompanying drawings.

10 The invention has relation, in general, to the depletion-detecting mechanisms, commonly termed feeler mechanisms, which are employed in looms for the purpose of forestalling complete exhaustion of the supply 15 of weft or filling contained in the working shuttle upon the lay of a loom. These mechanisms are contrived to "indicate", or "call", or "initiate", as it variously is termed, a change in the operation of the loom, upon 20 detecting that the progressive depletion of the said supply has reached a stage decided upon as a minimum. The change involves in some cases automatic replenishing of the working supply of weft or filling without 25 stoppage of the loom; in other cases, it involves stoppage of the loom without automatic replenishment; in still others it involves stoppage of the loom, with automatic replenishment during the stoppage, followed 30 by automatic restarting of the loom.

The invention is in the nature of a specific embodiment of the broad principles set forth in my application for U. S. Letters Patent filed April 29, 1916, Serial No. 94,334. In 35 the present instance, as also in the said application, the said broad principles are embodied in weft or filling feeler devices comprising a primary contact-member constituted by a feeler-member or finger that is 40 moved by the pressure of the shuttle-contained weft or filling-supply, at least during the earlier stages of said supply; a secondary, assisting or coadjutor, contact-member constituted by a second feeler-member 45 or finger that is given by the pressure of the said weft or filling-supply a movement differentially correlated with that of the primary contact-member; a controller-rest that is actuated through the movement of the 50 said primary contact-member, and in addition controlled by the said secondary or coadjutor contact-member and arranged to coact therewith in measuring the differential

of the positions given to the two contact-members; and a controller for the devices 55 that call a change in the operation of the loom. As in the application aforesaid, I combine with these elements, in accordance with the broad principles aforesaid, governing means which, so long as the primary contact-member is given by the pressure of the shuttle-contents a movement which exceeds 60 a certain amount, operates through the controller-rest to control the controller so as to prevent the parts that are controlled by the 65 controller from being called into action.

The present invention is characterized by a different construction and arrangement of controller-rest governing means, and by provisions for adjustment in connection therewith. In accordance with one part of the present invention, the said governing means consists in a finger projecting from the controller-rest below the secondary contact-member, and a controller-rest governing-finger occupying a position lower than the secondary contact-member, in which it intersects the forward portion of the path of movement of the controller-rest finger, in manner to prevent a change in the operation 75 of the loom from being called while the full-diameter feeler action continues.

Briefly stated, during the earlier stages of the weft or filling-supply, while the portion of the filling-supply which is presented to 85 at least the primary contact-member is of full diameter, or approximately the latter, the controller-rest governor governs the controller-rest, and thereby the controller, in such manner as to render the working of the 90 feeler devices an idle working at each movement throughout the said stages. After the forward movement of the primary contact-member has diminished to such an extent that it no longer carries the controller-rest 95 finger into engagement with the controller-rest governor, the secondary, assisting, or coadjutor contact-member begins to coöperate with the controller-rest in the functions of (1) measuring the final stages of the weft-supply, (2) detecting reduction of the final residue of the predetermined minimum, and (3) through the controller rendering the parts that are controlled by the latter operative to bring about a change in the operation 100 of the loom.

The invention is capable of being reduced to practice in various ways and by various mechanical constructions.

In the drawings,—

5 Figure 1 is a plan view of an illustrative embodiment of the invention in connection with devices of well-known character for calling a change in the operation of the loom.

10 Fig. 2 is an end elevation of the outer portion of the feeler mechanism of Fig. 1.

Fig. 3 is a front elevation of the parts that are represented in Figs. 1 and 2.

15 Figs. 4 and 5 are views similar to Figs. 1 and 2, but illustrating the action at the beat-up during the full-diameter stage of the supply of weft or filling contained in the shuttle on the lay.

20 Figs. 6 and 7 are views in plan and end elevation illustrating the action at the beat-up at the minimum stage.

25 Figs. 8, 9, 10, and 11 are views illustrating details.

Fig. 12 is an end elevation showing a second illustrative embodiment of the invention, on a larger scale.

25 Fig. 13 is a view showing the controller-rest governor of Fig. 12, detached.

Having reference to the drawings,—

30 The drawings show certain of the usual parts of a loom, including the lay-beam *a*, shuttle-box front-plate *b*, breast-beam *c*, weft-fork *d*, weft-fork slide *e*, mounted in a guideway *f* on the breast-beam, and weft-hammer *g*. At *h* is shown a loom-shuttle 35 occupying the shuttle-box, at *i* a bobbin contained within the shuttle, and *j* is the weft or filling that is wound upon and carried by the bobbin. The front wall of the shuttle is slotted as usual, as indicated at *h'*, to admit the working ends of the feeler-members or fingers to the interior of the shuttle to make contact with the surface of the mass of weft or filling. The usual slot 40 in the front-plate, with which the slot *h'*, of the shuttle-wall registers when the shuttle is home within the shuttle-box, is indicated at *b'*.

Having reference to the drawings, and first to Figs. 1 to 11,—

50 In the illustrative embodiment that is shown in the said figures, the contact-members constituted by the feeler-members or fingers 1 and 2 (shown separately in Figs. 8, 9, 10, 11,) are, for convenience, on the order of those shown and described in U. S. Letters Patent No. 940,600 granted Nov. 16, 1909 upon my application. That is to say, they are in the form of slides which are mounted side by side in guides provided in 55 upstanding portions of a small feeler-stand 32. Substantially as in the said Letters Patent, they are held in rearward positions, normally, by means of expanding spiral springs 60 31 and 41, surrounding their forwardly-extending stems or shanks 3 and 4, and con-

fined between the upstanding guide-lug 32^a at the front end of said feeler-stand and the front ends of the body-portions of the feeler-members or fingers. The said rearward positions are determined through the 70 contact of lateral projections 1^a, 2^a, Figs. 8 to 11, from the bodies of the feeler-members or fingers with the upstanding lug 32^b at the rear end of the said feeler-stand. As usual in feeler-mechanisms, the rear ends of 75 the feeler-members or fingers 1 and 2 are designed to enter the shuttle on the lay from the front as the lay goes forward. Both thereof are designed to be acted upon by the weft or filling-mass. In their normal 80 positions the feeler-members or fingers await the pressure or blow of the contents of the shuttle against their rear ends. They both are moved forward a short distance by such pressure or blow.

85 In the normal rearward position of the feeler-members or fingers 1, 2, the feeler-member or finger 1 projects a little farther rearward than the feeler-member or finger 2, as indicated in Figs. 1 and 2. The difference is somewhat greater than the predetermined "minimum" thickness, *i. e.*, the thickness of the final remainder of weft or filling on the filling-carrier in the shuttle when the change is called. It corresponds 95 with the bevel, inclination, or slope of the tapering conical tip-end of the filling-mass. Consequently, a cylindrical portion of the wound mass of weft or filling within the shuttle presented to the two feeler-members or fingers at the beat-up of the lay will cause the member 1 to begin to move forward before member 2 does, and will shift member 1 slightly relative to member 2.

100 The form, construction, mode of mounting 105 the feeler-members or fingers, and manner of applying spring-pressure, may vary more or less in practice. It is not essential in all cases that they should be slides.

110 The controller-rest 7 (shown best in Figs. 8 and 9) is a two-part finger that is hung by means of its body-portion 8 upon a pivot-pin 9 projecting transversely from an upstanding portion 10 at the front end of the feeler-member 1. Thereby the controller-rest is connected pivotally at its forward end with the feeler-member 1, and supported at such end. The downturned tip 71 of the rear end of the controller-rest lies normally upon the top surface of the feeler-member 2 120 at the rear of the rear end of an opening 5 in the latter feeler-member. By such surface of feeler-member 2 the controller-rest is supported normally at its free end, as in Fig. 2, for instance. So long as the free end 125 of the controller-rest is thus supported, it is locked by the secondary feeler-member 2. When feeler-member 1 is displaced forward relative to feeler-member 2 far enough to carry the tip 71 forward beyond the rear 130

end of opening 5, and into a position over said opening, the controller-rest is unlocked from feeler-member 2. The two parts of the controller-rest overlap each other for 5 portions of their length, and are connected together by means of a clamping screw 72, (shown best in Figs. 8 and 9) the stem of which occupies a longitudinal slot 7^a in the rear part of the controller-rest. By means 10 of an adjusting screw 7^b working in up-standing lugs with which the two parts of the controller-rest are furnished, the rear part may be adjusted upon and relative to the said body-portion 8, so as to vary the 15 extent to which the tip 71 projects rearward beyond the rear end of the opening 5 in the secondary feeler-member. By this adjustment the extent of relative displacement of feeler-member 1 with respect to feeler-member 2 necessary to carry tip 71 forward beyond the rear end of opening 5 and thereby 20 unlock the controller from feeler-member 2 may be varied.

The controller 44 consists mainly of a 25 rockshaft that is mounted in bearings 441, 441, provided in connection with the supporting stand 442 on which the small feeler-stand 32 is mounted. For coöperation with controller-rest 7, the outer end of the controller rockshaft has mounted thereon fixedly an arm 13 formed with a crank-pin 11 which lies upon the controller-rest 7. Through the engagement between the controller-rest and the crank-pin the crank-pin 30 11 is supported and the controller is locked from turning in the direction of the arrow shown in Fig. 1 upon its rockshaft, so long as the controller-rest itself remains locked through the engagement of its tip 71 with 35 the top surface of feeler-member 2.

The controller operatively controls the devices by which a change in the operation of the loom is called, by means of an arm 443 mounted fixedly on the inner end of 40 the controller rockshaft and provided with a crank-pin 444. The said crank-pin works in a slot 445 in a catch or dog 21 of usual character forming an element of the said devices. The said catch or dog in this instance is hinged at 22, Fig. 1, to the arm 23 forming a part of devices for controlling the operation of the loom. It is furnished with an engaging portion, shown as a lateral spur 24, for coaction with a suitable 45 55 striker. In the present instance, as ordinarily is the case in practice, the weft-hammer *g* is utilized as the striker, it being provided with a shoulder 25 adapted to engage the said spur, tooth, or shoulder, in 60 case the catch or dog should occupy its lowered position as the weft-hammer goes forward, for the purpose of pushing the catch or dog and arm forward and thereby bringing about the change in the operation 65 of the loom.

While the controller-rest remains locked by the secondary feeler-member, that is to say, normally, the controller is locked in a position which holds the catch or dog elevated so that its engaging portion 24 is 70 above the path in which the shoulder 25 of the weft-hammer travels as the weft-hammer swings forward. While this remains the case, the weft-hammer makes its forward stroke without engaging with the 75 catch. The weight of the catch 21 and of crank-arms 443 and 13, and the coöperating tension of a spring 33 connected with the controller rockshaft, tend to turn the controller in the direction indicated by the arrow thereon in Fig. 1, and operate to turn the controller in such direction when it is free to turn, to thereby lower the catch 21 into position to be engaged by the shoulder 25 of the weft-hammer. An elongated arch or bail 73 rising from the controller-rest 7 extends above and over the crank-pin 11 of the controller, for convenience in keeping the two parts in working relations with each other, and also for 80 enabling the weaver to lift the controller-rest so as to withdraw its tip 71 from the opening 5, when it is desired to do so manually, simply by taking hold of some convenient part of the controller and rocking 85 the latter in the direction opposite to that indicated by the arrow in Fig. 1.

The particular character and construction of the controller and the devices controlled thereby for calling a change in the operation of a loom are not material, so far as the invention is concerned.

The controller-rest governor 15 of this embodiment is a finger that is fixed to the rear portion of the stand 32 and projects 105 rearwardly therefrom below feeler-member 2. For coöperation with the controller-rest governor, the controller-rest is furnished with a finger 14, which projects down from the controller-rest below the 110 secondary feeler-member 2, and in line with the rear end of said stop-finger 15, at a short distance behind the said end. The acting portion of the controller-rest governing finger 15 occupies a position lower 115 than the secondary feeler-member in which it intersects the forward portion of the path of movement of the controller-rest finger 14. In this embodiment the latter is formed upon the tip 71 of the controller-rest and extends down through the opening 5 in the secondary feeler-member. To enable the time of action of the governing finger to be regulated so that engagement of finger 15 with finger 14 shall take place at the desired point in the movement of feeler-member 1 forward, the governing finger 15 is made adjustable forwardly and rearwardly. To this end, its shank occupies a hole in the rear upstanding portion of feeler-stand 32; 120 125 130

and is made fast therein by means of a clamping screw 15^a. This mode of mounting the finger 15 provides for adjustment of the same so as to locate its working end in proper position.

Having reference now to the operation of the devices which have been described, and the principles which are involved in such operation,—

- 10 As is well known, the weft or filling yarn carried by a filling-carrier occupying a loom-shuttle is drawn off from the said carrier in the direction of the length of the latter past the free end or tip of the filling-carrier, and issues from the shuttle through a delivery-eye with which the shuttle is furnished near the adjacent end thereof. To provide for the yarn being thus drawn off past the free end or tip of the filling-carrier, weft or filling is wound upon filling-carriers with a so-called cone-wind, as shown in various views of the drawing, namely in successive layers resembling conical or tapering shells, one outside another, 15 until the required length of wound mass is produced. The said wound mass is cylindrical exteriorly for a portion of its length, and has a conical end facing toward the tip of the filling-carrier. See Fig. 4. When 20 the spiral coils or turns constituting the exposed tapering layer of the cone-shaped end are drawn off, another similar layer is uncovered, and so on. The progressive withdrawal of the said layers shortens the wound 25 mass progressively until the yarn has been paid off from the filling-carrier back to the head or base-end of the latter.

When the shuttle is supplied with a filled filling-carrier, a portion of large diameter of 30 the wound mass of weft or filling is pressed against the feeling ends of the two feeder-members 1 and 2 at every feeling action, as 35 illustrated in Fig. 4, during the preliminary stage of the weft or filling-supply. This preliminary stage, which I call the 40 full-diameter stage, is a stage of long duration. It continues from the time when a fresh filling-carrier loaded nearly to its tip with weft or filling is brought into action, 45 to the time when the mass has become reduced in length so that the base of the cone or taper of the remainder or residue is just 50 about to be caused to extend to a point which as the lay goes forward will touch the feeling end of the feeler-member 1. The feeler-members 1 and 2 are located in such a position in the loom that they feel against the filling-mass at the usual place for feeler action, namely close to the enlarged head or 55 base of the filling-carrier. Consequently, a very large proportion of the filling-mass will have been paid out before the cone or taper of the remainder or residue is exposed to feeler-member 1.

60 65. In each feeling action during which the

full diameter or substantially the full diameter of the filling-mass is presented against the rearwardly-projecting end of feeler-member 1, the latter member is moved forward relative to the feeler-member 2, 70 thereby shifting the controller-rest forward so as to move its tip 71 forward past the rear end of opening 5, thereby unlocking the controller-rest from feeler-member 2. This would permit the controller to operate 75 to call the change in the operation of the loom if provision were not made thereagainst. Such change would be unnecessary. A change called at a time when the filling-mass occupying the shuttle is of anything like the proportions of that shown by Figs. 1 and 4, or in fact at any time during the full-diameter stage, would be objectionable 80 and undesirable. Accordingly, during the full-diameter stage, the controller-rest governor 15 is in action as shown in Fig. 5. A full or substantially full-diameter of weft or filling-supply operates at the beat-up of the lay to drive feeler-member 1 and the controller-rest 7 so far forward that the finger 14 strikes against the controller-rest governor 15 as shown in the view. Consequently, the controller-rest, if down, is raised and when raised is locked in an elevated position with the engaging portion 90 of the catch or dog 21 above and clear of the path of the shoulder 25 of the forwardly advancing weft-hammer.

As a result of the action of the controller-rest governor during the full-diameter stage, 100 any differential forward movement of the feeler-member 1 relative to feeler-member 2 is without either useful or harmful result or consequence, and is taken care of by means of the controller-rest governor so that 105 the controller-rest is given an elevated position.

When the weft or filling begins to pay out from the portion of the wound mass that makes contact with feeler-member 1, the extent to which such member is pushed forward will diminish and the difference between the strokes of the two feeler-members will decrease until the tapered residue stage in the consumption or paying-out of the 110 weft or filling from the shuttle is reached. In this stage, at the beat-up of the lay, the largest diameter of the residue or remainder of the filling-mass is presented against the feeler-member 2, while the conical or tapering portion of the said residue or remainder is presented against the feeler-member 1. A smaller diameter, therefore, is presented 115 to the feeler-member 1 than the diameter which is presented to the feeler-member 2. 120 Because of the said difference in diameters during this stage the rear end of feeler-member 1 is arranged to project normally a corresponding distance farther rearward than the rear end of feeler-member or finger 130

2, as stated hereinbefore, in order that during the tapered residue stage, as the filling-mass is carried forward toward the feeler-members, it will touch the feeling ends of the two members simultaneously, or approximately so. For a time the two feeler-members will be driven forward in unison, or practically so, by the pressure of the filling-mass against their feeling ends, with the tip of controller-rest 7 lying upon the top surface of the feeler-member 2 at the rear of opening 5 and supported thereby. While this continues, the controller is locked by feeler-member 2 in the position in which it supports the catch 21 out of the path of the shoulder 25 of the weft-hammer. At a certain point during this stage, the progressive decrease in the diameter of the portion of the filling-mass which acts against the feeler-member 1 will 20 reduce the extent of the forward movement of said feeler-member and the controller-rest 7 pivoted thereto, so that the finger 14 of the controller-rest does not touch the controller-rest governor 15. From that time 25 on the controller-rest governor does not act and is not needed to act.

As the filling continues to be drawn off from the "tapered residue" the various diameters of the latter become smaller and the 30 forward movement given to the feeler-members at every feeling action further diminishes, that of the feeler-member 2 more rapidly than that of feeler-member 1. A measuring action begins just as soon as the 35 extent of the forward movement of feeler-member 2 begins to grow less than that of feeler-member 1. It involves a resumption of differential movement of the two feeler-members, the feeler-member 1 leading the 40 feeler-member 2 as the two feeler-members are driven forward at each feeling action. This differential movement produces at each successive beat-up a movement of the tip 71 of controller-rest 7 forward upon the top 45 surface of feeler-member 2, and toward the edge of the opening 5. The relative movement increases in extent at each successive beat-up, in proportion as the remaining filling diminishes in diameter, and consequently 50 the tip 71 approaches closer and closer toward the edge of the opening 5, until finally, when the relative movement of feeler-member 1 forward with respect to feeler-member 2 carries the said tip 71 of the controller-rest 7 off the edge of the opening 5, as in 55 Figs. 6 and 7, the controller-rest and controller will be unlocked, and under the influence of the spring 33 and gravity the controller will rock so as to place the engaging portion 24 of catch 21 in position to be engaged by shoulder 25 of the weft-hammer. Thereby the said catch and the arm 23 will 60 be operated so as to bring about the prearranged change in the operation of the loom. 65 Through adjustment of the tip-carrying

part of the controller-rest by means of screw 7^c so as to cause tip 71 to lap rearward of the rear edge of opening 5 more or less, the release of the controller-rest may be caused to take place sooner or later, according as it 70 is desired to leave more or less filling upon the filling-carrier when the change is called.

Ordinarily in the operation of a loom having the just described feeler mechanism applied thereto, while the lay is rearward the 75 weft-hammer also occupies a rearward position with the shoulder 25 a short distance, somewhere about a quarter of an inch, to the rear of the engaging portion 24 of the catch 21. The weft-hammer remains in this position while the lay goes forward. As the lay approaches front center the filling-mass contained in the shuttle in the shuttle-box of the lay strikes the rear ends of the feeler-members and drives them forward, the contact with the full diameter of filling-mass taking place under the usual adjustments when the lay is somewhere about half an inch or three-eighths of an inch back from the most forward point reached by it. When 90 the lay is about a quarter of an inch back from the said most forward point, the weft-hammer begins to move forward. The contact of the finger 14 of the controller-rest with the fixed stop 15 in the final portion of 95 the movement of the lay throws the controller-rest upward, gives a quick turn to the controller, and also throws the catch 21 upward, and the continued forward movement of the weft-hammer carries the shoulder 25 100 forward under the engaging portion 24 of the catch 21 while the catch is thus elevated. As the weft-hammer goes forward under the engaging portion 24 the top of the weft-hammer behind the shoulder 25 bears against 105 the underside of the said engaging portion so as to support the catch until the rearward movement of the weft-hammer withdraws the shoulder 25 out from under the spur. The shoulder 25 passes forward under the 110 engaging portion 24 of the catch after the finger 14 has passed forward upon the controller-rest governor 15 and while it is either resting upon the top of the said governor or poised by momentum slightly above the 115 same. The weft-hammer follows the lay rearward, but the top of the weft-hammer does not pass out from under the spur of the catch, and continues to support the catch and the controller, until the lay has moved 120 rearward a considerable distance.

The controller-rest governor 15 has two functions. One thereof is to prevent the feeler devices from acting to call a change in the operation of the loom at any time during 125 the "full diameter" stage (shown in Figs. 1 to 5) of the filling-mass on the carrier in the shuttle. The other function is to raise the controller-rest sufficiently high as it goes forward with the feeler-member 1 to insure 130

that, as the said feeler-member and the controller-rest are driven rearward again by the action of the spring 31 as the lay and shuttle retreat rearwardly, the tip 71 of the controller-rest shall land on the top surface of the feeler-member 2 at the rear of the opening 5, and not drop into the said opening.

In the embodiment shown in Figs. 12 and 13, the finger 141, that co-operates with the controller-rest governor, is provided in connection with the body-portion 8 of the controller-rest, and projects downward therefrom at a point some distance in front of the opening 5 in the feeler-member 2. The controller-rest governor in this embodiment is a substantially horizontal finger 151 having its front end bolted to the under side of the forwardly projecting portion of the feeler-stand 32. The said finger is located below the level of the feeler-members. The adjustment of the working position of the controller-rest governor forwardly and rearwardly is provided for by furnishing the forward end of the said governor with an elongated slot 151^a accommodating the stem of the bolt or screw 151^b which fastens the said finger to the controller-stand.

Other changes in the form, etc., of the parts may be made in practice. The specific mode of operation may vary more or less in practice.

The adjustment of the governing finger forward or rearward in the loom varies the stage in the progressive decrease in diameter of the contacting portion of the filling-mass at which the governing action shall cease. Such adjustment also compensates for shift or adjustment of feeler-stand 32 forward or rearward upon the outstanding horizontal ledge 442^a of supporting-stand 442. The feeler-stand is secured by means of a clamping screw 32^b in the position in which it is set or adjusted upon the said ledge.

What is claimed as the invention is:—

45. 1. Weft-feeler mechanism comprising devices for calling a change, a controller for such devices, a primary feeler-member, a controller-rest actuated by the said feeler-member, a secondary feeler member controlling said controller-rest, a finger normally projecting from said controller-rest below the secondary feeler-member, and a controller-rest-governing finger occupying a position lower than the secondary feeler-member in which it intersects the forward portion of the path of movement of said controller-rest finger.

60. 2. Weft-feeler mechanism comprising devices for calling a change, a controller for such devices, a primary feeler-member, a controller-rest actuated by the said feeler-member, a secondary feeler-member controlling said controller-rest, a finger nor-

mally projecting from said controller-rest downward below the secondary feeler-member, and a fixed controller-rest-governing finger occupying a position in which its acting rear end is lower than the secondary feeler-member and intersects the forward portion of the path of movement of said controller-rest finger.

3. Weft-feeler mechanism comprising devices for calling a change, a controller for such devices, a primary feeler-member, a controller-rest actuated by the said feeler-member, a secondary feeler-member controlling said controller-rest, and a controller-rest governor having means for adjusting its time of action.

4. Weft-feeler mechanism comprising devices for calling a change, a controller for such devices, a primary feeler-member, a controller-rest actuated by the said feeler-member, a secondary feeler-member controlling said controller-rest, and a controller-rest-governor having means for adjusting its working position forwardly and rearwardly.

5. Weft-feeler mechanism comprising devices for calling a change, a controller for such devices, weft-feeler-means, a controller-rest controlled by the said feeler-means, and a controller-rest-governor which renders said devices inoperative to call a change while the diameter of the filling-mass exceeds a predetermined amount, the said controller-rest governor having means for adjusting its time of action.

6. Weft-feeler mechanism comprising devices for calling a change, a controller for such devices, weft-feeler-means, a controller-rest controlled by the said feeler-means, and a controller-rest-governor which renders said devices inoperative to call a change while the diameter of the filling-mass exceeds a predetermined amount, the said controller-rest governor having means for adjusting its working position forwardly and rearwardly.

7. Weft-feeler mechanism comprising devices for calling a change, a controller for such devices, a primary feeler-member, a controller-rest actuated by the said feeler-member, a secondary feeler-member controlling said controller-rest, means to adjust the said control so as to determine the minimum residue to be left upon the filling-carrier, and a controller-rest-governor having provisions for adjusting its time of action.

In testimony whereof I affix my signature in presence of two witnesses.

SIMEON S. JACKSON.
